UNITED STATES PATENT OFFICE

2,414,848

STEAM GENERATOR

John Phillips Badenhausen, Philadelphia, Pa.

Application March 3, 1944, Serial No. 524,865

3 Claims. (Cl. 122—365)

1

This invention relates to steam generators and more particularly to apparatus for preventing priming of the same.

Many steam generators now in use, in addition to the customary steam drum or steam and water drum, have a large lower water drum or mud drum which in many instances is of the same or even of larger diameter than the steam drum or the steam and water drum. In the operation of such steam generators, it frequently happens that the steam pressure in the steam generator, instantaneously and by reason of sudden steam demands, may drop ten or fifteen pounds. This drop in internal pressure may not even be noticeable on the pressure gage because of its rapidity or for other reasons. In steam generators having large mud drums, the large volume of water in the boiler tubes and in the mud drum has a high expansion potential and substantial portions of the water tend to flash into steam immediately upon the occurrence of the pressure drop. The sudden flash into steam of the large quantity of water results in efforts of the steam contained in the water to find relief. The water and the steam released therein travel together upwardly through the tubes to the steam drum or steam and water drum, in many instances through the downcomer tubes. Considerable quantities of steam and water may be forced through the superheater without vaporization. The discharge of the water may cause considerable difficulties by carrying solids in solution or in suspension into various parts of the power plant and the water may damage the blading of the turbine.

In accordance with the present invention provision is made for reducing the amount of water which is capable of causing flash generation of steam upon reduction of pressure while maintaining adequate fluid available to feed the tubes and maintain proper circulation.

In accordance with the present invention also, provision is made for separating and segregating a considerable quantity of the water in the mud drum or water drum which is capable of contributing to the priming whereby the operation of the boiler will be greatly improved.

In accordance with the present invention also provision is made for the correction of priming difficulties in boilers now in use.

Other advantages of the invention will be apparent from the annexed specification and claims.

The nature and characteristic features of the invention will be more readily understood from

2

the following description, taken in connection with the accompanying drawing forming part hereof, in which:

Figure 1 is a vertical central sectional view through a conventional steam generator indicating the manner of use of the present invention;

Fig. 2 is a fragmentary transverse sectional view through a mud drum showing the manner of installing the apparatus in accordance with the present invention;

Fig. 3 is a fragmentary longitudinal sectional view showing certain details of construction; and

Fig. 4 is an enlarged fragmentary longitudinal sectional view showing further details of construction.

It will, of course, be understood that the description and drawing herein are illustrative merely, and that various modifications and changes may be made in the structure disclosed without departing from the spirit of the invention.

Referring more particularly to Fig. 1 of the drawing a boiler 10 of conventional type is illustrated for purposes of explanation of the invention. The boiler 10 shown is of the Stirling type, with a chain grate stoker 11, although it will of course be understood that the invention is not restricted to use of boilers of this specific type or fired in this manner. The boiler 10 illustrated preferably includes a lower water drum or mud drum 12, a front upper drum 13, an intermediate upper drum 14 and a rear steam and water drum 15, the drums 13, 14, and 15 being preferably arranged with their axes parallel to that of the lower drum 12. The lower water drum or mud drum 12 may have the usual manholes 16 at the ends thereof.

Banks of spaced steam generating riser tubes 17 are provided extending from the water drum 12 or mud drum 12 to the front upper drum 13, the tubes 17 being exposed to the radiant heat of combustion.

Banks of spaced riser tubes 18 for steam generation are provided connecting the lower water drum or mud drum 12 to the central drum 14 and banks of spaced downcomer tubes 19 are provided for connecting the steam and water drum 15 with the lower water or mud drum 12.

The drum 13 and the drum 14 are preferably connected by a bank of tubes 20 extending therebetween below the water level thereof and by a bank of tubes 21 extending therebetween above the water level thereof. The drum 14 is also preferably connected to the drum 15 by a bank of tubes 22 extending therebetween above the water level

thereof. The drum 15 has a steam delivery pipe 23 connected thereto for the discharge of the steam generated in the steam generator and for the delivery of the steam to a superheater 24, preferably mounted in the space between the bank of tubes 17 and the bank of tubes 18.

Suitable baffles 25 and 26 are provided for dividing the interior space into a plurality of passes and for directing the gases in heat exchange relationship with the tubes of the bank of tubes 17, the tubes of the bank of tubes 18 and the tubes of the bank of tubes 19. The exhaust gases of combustion are discharged through a duct 28 to an induced draft fan (not shown) for discharge to a stack (not shown).

The combustion chamber 27 may be provided with any suitable means for supplying heat for steam generation and, in the particular boiler illustrated, a chain grate stoker 11 is shown diagrammatically.

In accordance with the present invention an interior casing or shell 30 is provided and is mounted in the lower water drum or mud drum 12 for the purpose of confining the major portion of the water contained in the water drum or mud drum 12 as hereinafter pointed out. The interior casing or shell 30 is preferably cylindrical in shape and is constructed of parts capable of insertion through the manholes 16 of the drum 12 for assembly within the interior of the drum 12. For this purpose a plurality of plates 31 are provided, the plates 31 preferably being curved in transverse cross section so as to be substantially concentric with the drum 12 when mounted in position. These plates 31 also preferably extend from one end of the drum 12 to the other end of the drum 12 and have flanges 32 at their ends for engagement by end cover plate members 33 as illustrated in Fig. 3. The plates 31 are supported at suitable intervals along their length by posts 34 welded or otherwise secured to the drum 12. The posts 34 preferably have reduced end sections 35 for the reception of the plates 31 and the reduced end sections 35 have slots 36 for engagement by tapered wedges or keys 37 for locking the plates 31 in position. The end cover plates 33 are preferably secured to the flanges 32 of the longitudinal plate members 31 in a similar manner by keys 37 extending through slots 36 in the end members 35a.

The interior casing or shell 30 is preferably open at the bottom as at 39 for access of water into the interior of the casing 30 and a plurality of small openings 40 are provided in the upper plate sections 31 for the slow discharge of steam formed within the shell or interior casing 30 as hereinafter pointed out.

The manner of use of the apparatus in accordance with the present invention will now be explained. The posts 34 are preferably mounted in the drum 12 and the shell 30 is assembled by placing the respective plate sections 31 in position with their longitudinal side edges overlapping. The tapered wedges or keys 37 are inserted and forced into locking engagement and the end cover plates 33 are mounted and secured in position by wedges or keys 37.

With the shell or interior casing 30 in place in the interior of the water drum or mud drum 12 the steam generator may be operated in the customary manner for the production of steam and for the delivery therefrom through the steam main 23 to the superheater 24. The water passing downwardly through the downcomer tubes 19 or otherwise supplied to the drum 12 will pass

around the exterior of the shell or interior casing 30 to the lower ends of the tubes 17 and of the tubes 18. If the pressure in the steam generator drops, by reason of increased demand for steam, and even if this pressure drop is of very short duration there is an immediate tendency of the water to flash into steam at the reduced pressure. This occurs even without the necessity for supplying additional heat thereto from the combustion gases.

For steam at a pressure of the order of 225 pounds per square inch, the volume of a pound of steam is of the order of approximately 100 times that of the volume of the water at the same pressure. For steam at a pressure of the order of 1200 pounds or 1400 pounds per square inch, the volume of a pound of steam is of the order of fifteen times that of the volume of a pound of water at the same pressure. It will thus be seen that upon the occurrence of a pressure drop even of a few pounds there is a considerable tendency of the water in all parts of the boiler to flash into steam and increase its volume. Such increase heretofore has been effective to impel water and steam in the tubes 17, the tubes 18, and particularly in the downcomer tubes 19, upwardly with resultant priming. The shell or interior casing 30 confines the major part of the water in the water drum or mud drum 12. Upon a drop in pressure the steam which tends to form within the shell or casing 30 is retained therein and is discharged or relieved at a slow rate through the openings 40 in the upper part of the shell 30. The opening 39 at the bottom is also preferably such as to prevent the rapid displacement of the water and the static head of the water outside the shell or casing 30 tends to prevent the rapid discharge at this location. The only water available to flash into steam and pass upwardly in the steam generator is that contained in the tubes of the banks of tubes 17, 18 and 19 and outside the casing 30 in the water drum or mud drum 12. This quantity of water is relatively small and is not sufficient to cause any priming.

I claim:

1. In a steam generator having a steam drum and a water drum and banks of tubes extending between said drums and connected thereto at their terminal ends, the combination of means for preventing priming of said steam generator, said means including an interior closed water confining casing mounted within said water drum for reducing the effective volume of water therein capable of causing priming, said casing being spaced from the walls of said water drum and from the terminal ends of said tubes for permitting the free flow of water around said casing and with respect to the terminal ends of said tubes, said casing having end cover members for closing the ends of said casing, and said casing having a restricted water access opening at the bottom thereof for preventing the rapid discharge of water confined within said casing.

2. In a steam generator having a steam drum and a water drum and banks of tubes extending between said drums and connected thereto at their terminal ends, the combination of means for preventing priming of said steam generator, said means including an interior closed water confining casing mounted within said water drum for reducing the effective volume of water therein capable of causing priming, said casing being spaced from the walls of said water drum and from the terminal ends of said tubes for per-

mitting the free flow of water around said casing and with respect to the terminal ends of said tubes, said casing comprising curved plate members carried by the wall of said drum and longitudinally disposed with respect thereto, and end cover members for closing the ends of said casing, and said casing having a restricted water access opening at the bottom thereof for preventing the rapid discharge of water confined within said casing.

3. In a steam generator having a steam drum and a water drum and banks of tubes extending between said drums and connected thereto at their terminal ends, the combination of means for preventing priming of said steam generator, said means including an interior closed water confining casing mounted within said water drum

for reducing the effective volume of water therein capable of causing priming, said casing being spaced from the walls of said water drum and from the terminal ends of said tubes for permitting the free flow of water around said casing and with respect to the terminal ends of said tubes, said casing comprising curved plate members carried by the wall of said drum and longitudinally disposed with respect thereto, and end cover members for closing the ends of said casing, and said casing having a plurality of restricted openings at the upper part thereof for the slow discharge of steam formed within said casing and a restricted water access opening at the bottom thereof for preventing the rapid discharge of the water confined within said casing.

JOHN PHILLIPS BADENHAUSEN.
